[57] CLAIM

The ornamental design for a rotatable merchandising display stand, as shown and described.

DESCRIPTION

FIG. 1 is a perspective view of a rotatable merchandising display stand showing my new design;

FIG. 2 is a top plan view thereof;

FIG. 3 is a side elevational view the other sides being identical;

FIG. 4 is a bottom plan view thereof;

FIG. 5 is a perspective view with the shaft of the stand rotated 45°; and

FIG. 6 is an enlarged perspective view of one of the units shown separately for convenience of illustration.
